CLAIM

The ornamental design for an electric warming harness, as shown and described.

DESCRIPTION

FIG. 1 is a front view of a heating harness showing my new design;

FIG. 2 is a rear view thereof;

FIG. 3 is a side view thereof, the opposite side being the same;

FIG. 4 is an enlarged cross-section taken along line 4—4 of FIG. 3;

FIG. 5 is an enlarged side view of the thermostat; and, FIGS. 6, 7, 8 and 9 are the front, side, rear, and opposite side views of the thermostat and plug-in system for temperature control, respectively.

FIG. 1

FIG. 2

FIG. 4

FIG. 5

FIG. 6

FIG. 7

FIG. 8

FIG. 3

FIG. 9
